UNITED STATES PATENT OFFICE

ALBERT J. GRAF, OF WESTFIELD, NEW JERSEY, ASSIGNOR TO R. HOE & CO., INC., OF NEW YORK, N. Y., A CORPORATION OF NEW YORK

SHEET HANDLING MECHANISM FOR PRINTING MACHINES

Application filed April 10, 1930. Serial No. 443,140.

This invention relates to printing machines which deliver the printed product in sheet form and especially to the mechanism for raising and lowering the support on which the sheets are piled or stacked. As herein shown, the mechanism is arranged for use with a delivery, but it will be understood that with slight modifications, it can be adapted for use with a feeder.

- 10 An object of the invention is to provide a mechanism that will automatically raise or lower a support for a pile of sheets, at a rate that will maintain the top of the pile at the proper level for feeding the sheets therefrom when operating with a feeder, or for receiving the sheets when operating with a delivery.

Another object of the invention is to provide a mechanism by means of which, the pile support may be quickly raised or lowered for loading, unloading, and to position the top of the pile at the proper operating level.

Another object of the invention is to provide a driving mechanism that is normally connected to the pile support, but which is automatically disconnected when the support reaches the limits of its travel.

It is also an object of the invention to provide a pile support operating mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

The preferred embodiment of the invention is illustrated in the accompanying drawings, wherein:

Figure 1 is a view of a portion of a printing machine showing a portion of a pile support with the mechanism for operating it that is the subject of the invention;

Figure 2 is a vertical view partly in section, of the operating mechanism shown in Figure 1, as viewed in the direction of arrow 2 of Figure 1;

Figure 3 is an enlarged view of a portion of the mechanism shown in Figure 1;

Figure 4 is a sectional view of the mechanism shown in Figure 3 as viewed on the dotted line A—A and in the direction of arrow 4;

Figure 5 is an enlarged view partly in section, showing the yieldable clutch member that is shown in Figures 1 and 2;

Figure 6 is a detail plan view partly in section showing the operating clutch member as seen in the direction of arrow 6 of Figure 4; and

Figure 7 is another detail view showing the operating clutch member in section as seen in the direction of arrow 7 of Figure 4.

The drawings show the invention adapted for use with a delivery pile support for a printing machine from which the product is delivered in sheet form. The numeral 11 indicates a base frame for a printing machine, 12 indicates a side frame, and 13 indicates the main cross member of the pile support. A pair of arms, one of which is shown at 14, are pivotally connected by the pin 15 to lugs formed on the cross member 13. The arms 14 serve to support the platform 16 on which the sheets are piled. The pile support is suspended from the machine frame in a manner heretofore known, and includes a pair of chains, one of which is shown at 17. One end of each chain is secured to an eye bolt 18 that is screwed into the cross member 13, and the other end is secured to an eye bolt 19, which passes through a hole in a bracket 21, that is secured to the cross member 13, nuts 22 which are threaded on to the eye bolt 19 being provided for adjustment. The intermediate portion of the chain which is diagrammatically indicated, passes over sprockets indicated at 23 and 24. Sprocket 23 is secured to a shaft 25, which is rotatably supported in the side frames 12, while the sprocket 24 is rotatably supported on a stud secured to the base 11. The worm wheel 26 is secured to the shaft 25 and is engaged by

a worm 27 rotatably supported on the shaft 28, which in turn is rotatably supported in bearing brackets 29 and 31 suitably secured to the side frame 12. A clutch comprises members 32 and 33. The member 32 is secured to the hub of the worm 27 and the member 33 is arranged to slide on a feather 34 on the shaft 28. A cup shaped member 35 is secured to the shaft 28 and provides a holder 10 for a spring 36, which bears against the under side of the clutch member 33, thus holding it in engagement with the clutch member 32, and acting to drive the worm wheel 26. It will be understood that by rotating 15 the shaft 28, that the pile support may be raised or lowered as desired.

In accordance with common practise in the art, the delivery of a printing machine includes a pair of chains, one of which is diagrammatically indicated by the lines 37 and 37', and it passes over sprockets indicated diagrammatically at 38 and 39, the latter being shown at 39 on Figure 2. It will be understood that these chains are connected by cross bars carrying grippers which engage the sheets and carry them from the printing cylinders to a point over the delivery pile where they are released, and that they are driven by the printing machine and in properly timed relation to the printing cylinders. The sprocket 39 is secured to the shaft 41, which is rotatably supported in the frame 12. The pinion 42 is also secured to the shaft 41, and meshes with the gear 43, rotatably supported on the stud 44. A bracket 45 is secured to the gear 43 and carries a crank pin 46. An arm 47 serves to connect the crank pin 46 with a pin 48, carried by the arm 49, that is rotatably supported on the stud 51, secured to a bracket 52, that in turn is secured to the frame 12 by means of bolts 53. The arm 49 carries a pin 54, on which the pawl 55 is pivoted. The pawl engages with a ratchet wheel 56 rotatable on the stud 51. A 45 spring 57 is secured to the arm 49 and acts to push the pawl 55 into engagement with the ratchet wheel 56. A bevel gear 58 is secured to the ratchet wheel 56 and meshes with the bevel gear 59, which is formed on a sleeve 50 61, which turns on the shaft 28 and is rotatably supported by the split bearing 62, one half of which is formed integral with the bracket 52, the other half of the bearing being in the cap 62'. The sleeve 61 is formed 55 with a clutch member 63 on its lower extremity and a similar clutch member 64 is formed on the collar 65 that is keyed to the shaft 66.

A double operating clutch is provided, that is shown in detail in Figures 6 and 7. It consists of an outer ring 67, having a groove 68, in which rollers 69 are fitted to run. The rollers turn on pins secured to a forked operating lever 71, that is pivoted at 72 to lugs formed on the bracket 52. As shown in Fig-

ure 4, the clutch has an inner ring 73, fitted to slide within the outer ring 67, and having a clutch face 74, on its upper side that is adapted to engage the clutch member 63, and a similar clutch face 75 on its lower side 70 adapted to engage the clutch member 64. The clutch ring 73 is fitted to slide on a feather 76 on the shaft 28, and is provided with a spring 77, one end of which abuts against the flange 73' on the inner clutch ring, while the other end abuts against the flange 67' on the outer ring. Pins 78 that are shown in Figure 6, are secured to the inner clutch ring 73 and operate in grooves 80 cut in the flange 67' of the ring 67, and similar pins 79 are secured to the ring 67 and operate in grooves cut in the flange 73'. It will thus be understood that a spring abuts against the pins and the flanges and tends to hold the clutch member in a central position with respect to the forked lever, but that the latter may be moved either up or down to engage the clutch, and if the shafts are not in the engaging position, the spring will be compressed, and when the driving member is rotated, the clutch will then spring into engagement.

In the drawings, the forked lever 71 is shown in the neutral position and it is held there by means of the notched bar 81, which is pivotally connected at 81' with the forked lever 71. A stud 82 is secured to the cap 62' and is provided with a pin 83 that engages with notches cut in the bar 81. The spring 84 acts to rotate the bar on the pivot 81' and into engagement with the pin, thus holding the forked lever either in the neutral position as shown, or in one of the clutch engaging positions. A handle 85 is secured to an arm 86, that is fastened to a guard 87 and rotates on the stud 51. The periphery of this guard is concentric with the periphery of the ratchet wheel 56, but is made with a larger diameter except at a cut-away portion 87'. A pin 55' projects from both sides of the pawl 55 to which it is secured. It will be understood that when the pawl 55 is traversing the cut-away portion of the guard that it will engage the ratchet wheel 56, but that when it reaches the portion that is not cut away, the pawl will be lifted out of engagement with the ratchet wheel. Thus, by moving the handle 85, the effective travel of the pawl 55 may be varied. A scale 88 is secured to the side frame 12 and serves as a gauge for setting the guard. The lower side of the guard is formed with teeth at 89 that are engaged by a latch 91 that slides in a hole 92 in the bracket 52, and is pressed into engagement with the guard by the spring 93, thus providing means for holding the guard in the desired position.

A second guard member 94 is pivoted at 95 on an arm 96 that is part of the gear housing. The guard member 94, under normal conditions, is concentric with the cut-away

portion of the guard 87. When the impression of the printing cylinders of the machine is tripped, the link 97 which is shown pivotally connected to the arm 98 of the guard 5 member 94, is moved toward the left (in Figure 1), thus raising the guard member 94 to a position where the pin 55' will prevent the pawl from engaging the ratchet 57. The shaft 66 is connected by worm gearing 10 in a well known manner with a shaft 101 that is coupled to the motor 102. It will thus be understood that when the forked lever 71 is thrown downward, that the motor 102 will be connected to the shaft 28, and will rotate 15 the gear 26 to quickly raise or lower the pile support as desired. When the lever 71 is thrown upward, it will connect the shaft 28 to the sleeve 61 which is driven through the gearing by means of the pawl and ratchet 20 mechanism that is connected to the sprocket 39 and is thus driven from the delivery of the printing machine and in timed relation thereto. If the pile support reaches the limits of its travel or meets with an obstruction, the 25 additional load imposed on the parts will act to compress the spring 36, and allow the spring coupling members 33 and 34 to separate, thus disconnecting the shaft 28 from its drive, this action being effective when the 30 pile elevating mechanism is being driven either by the motor or by the printing machine.

In operation, the pile support will be raised by the motor to its position ready to receive 35 sheets, and the handle 85 will be adjusted to the correct feeding position. When thick paper is being handled, it will be adjusted to allow the pawl to advance the ratchet wheel several notches at each stroke, but with thinner paper, it will be adjusted for a shorter 40 travel thus lowering the pile support gradually as the sheets are piled on top of it. When the feeding mechanism fails to deliver a sheet to the printing cylinders, it is common practise to trip the impression and with 45 the mechanism shown herein, this results in disconnecting the mechanism that is used to lower the pile, and it is therefore possible to operate the press when not printing without 50 lowering the pile, but if the impression is thrown on, the pile operating mechanism is automatically connected.

What I claim is:

1. In a mechanism for operating a vertically movable pile support for a sheet fed printing machine, means operated by the machine, for moving the pile support at a slow speed, to maintain the top of the pile at a substantially constant level, means operated by a 55 separate source of power for moving the pile support at a higher rate of speed, and a safety device for disconnecting the said means when the motion of the pile support is obstructed.

2. In a mechanism for operating a verti-

cally movable pile support for a sheet fed printing machine, means operated by the machine for moving the pile support at a relatively slow variable speed to maintain the top of the pile at the proper level, means 70 operated by power from a separate source, to move the pile support at a higher rate of speed, and a safety device for automatically disconnecting the said means when the motion of the pile support is obstructed.

3. In combination with a printing machine having a sheet delivery, a mechanism for operating a pile support for the delivery, a pawl operated means connected to a moving part of the machine for moving the support vertically, means to adjust the effective motion of the pawl to vary the normal rate of movement of the pile support, a motor geared to move the support vertically, a two way clutch arranged to permit moving the support by either the means connected to the printing machine or by the motor, and a yielding coupling adapted to disconnect the mechanism for operating the pile support when said support reaches its limits of travel. 85

4. In a pile delivery mechanism for a printing machine, a vertically movable pile support, means for lowering the support at a speed that maintains the top of the pile at a substantially constant level, said means 90 acting only while the machine is delivering sheets to the pile, other means including a motor geared to move the pile support at a higher rate of speed than the first mentioned means, clutch mechanism arranged to permit moving the pile support by either of the said means, and a yielding connection arranged to disconnect the means for moving the pile support when it reaches the limit of its travel. 95

5. In a mechanism for operating a vertically movable pile support, a flexible lifting members connected to the support, a worm wheel operably connected to said members, a driving shaft, a worm gear rotatable on the shaft and secured to one member of a clutch, the other member of which is caused to rotate with the shaft, yielding means arranged to normally hold the clutch members in engagement with each other, means for rotating the shaft at the speed required to maintain the top of the pile at a substantially fixed level, and a motor arranged to rotate the shaft at a higher speed; said yielding means being arranged to yield when the movement of the pile support is obstructed. 110

In testimony whereof, I affix my signature.
ALBERT J. GRAF.
